ELECTRIC SWITCH

John G. Jackson, Detroit, Mich., assignor to
 Square D Company, Detroit, Mich., a corpora-
 tion of Michigan

Application October 6, 1930, Serial No. 486,856

5 Claims. (Cl. 200—166)

This invention relates generally to electric switches and refers more particularly to knife or jaw switches.

One of the essential objects of the invention 5 is to provide a switch of this type in which the jaw thereof has a cup-shaped recess for receiving and has co-acting ribs to form line contact with the knife blade or bar of the switch.

Another object is to provide a switch in which 10 the cup-shaped recess forms the first stage of contact upon closing the switch and forms the final stage of contact on opening the switch, the action being such that the blade can be readily inserted into the recess and will form a sufficiently good contact to prevent undue heating 15 or arcing.

Another object is to provide a switch in which the ribs constitute the second and final stage of contact and exert a higher pressure against 20 opposite sides of the blade than that exerted by the walls of the cup-shaped recess.

Another object is to provide a switch in which the jaw plates are provided with spring backers that lie flat against the jaw plates and cause 25 the ribs aforesaid to grip firmly and positively the knife blade or bar so that a better contact between the parts is obtained.

Another object is to simplify, improve generally and render more efficient switch structures 30 of the type described.

Other objects, advantages, and novel details of construction of this invention will be made more apparent as this description proceeds, especially when considered in connection with the 35 accompanying drawing wherein:

Figure 1 is an edge elevation of a switch embodying my invention and showing the knife blade about to enter the jaw;

Figure 2 is a view similar to Figure 1 but 40 showing the parts after the knife blade is in engagement with the jaw;

Figure 3 is a side elevation of the structure illustrated in Figure 1, omitting the knife blade.

Referring now to the drawing, A is a terminal 45 bar of good conducting material such as copper; B is a jaw embodying my invention extending upwardly from the bar A; and C is a movable knife blade or bar engageable with the jaw B to close an electric circuit. As shown, the terminal bar A is substantially L-shape and has a 50 flat base 1 attachable to a support (not shown). The jaw B preferably comprises a pair of substantially parallel plates 2 and 3 respectively and a pair of spring backers 4 and 5 respectively for said plates. Preferably the plates 2 and 3 are

secured at their lower ends to opposite sides of the upright portion 6 of the terminal bar A and are provided at their upper ends with opposed inwardly projecting transversely extending outwardly opening substantially channel shape embossed portions or ribs 7 and 8 respectively and opposed outwardly extending curved end portions 9 and 10 respectively. As shown in Figure 1, the ribs 7 and 8, curved end portions 9 and 10 and intermediate parallel portions 11 and 12 respectively of the plates form a cup-shaped recess 5 for the reception of the knife blades C. The spring backers 4 and 5 are preferably plates of spring metal that are flat against the outer faces of the parallel plates 2 and 3 and extend from 15 the lower ends thereof to points below but adjacent to the ribs 7 and 8. Preferably rivets 13 extend through the upstanding portion 6 of the terminal bar at spaced points thereof and constitute a common securing means for the plates 20 2 and 3 and spring backers 4 and 5.

In use when the knife blade C is inserted between the plates 2 and 3 the curved end portions 9 and 10 of said plates will guide the knife blade inwardly between the plates. The blade C 25 will first contact with opposite sides of the cup shaped recess and will then be engaged by the ribs 7 and 8. The spring backers 4 and 5 resist the separation of the ribs 7 and 8, hence when the ribs 7 and 8 are separated by the 30 knife blade C, the backers 4 and 5 are under tension and cause the said ribs to press against and firmly grip the knife blade. In fact, the construction and arrangement of the ribs is such that an extremely fine line contact with opposite 35 sides of the knife blade C is obtained. In Figure 1 it will be noted that the knife blade C is in a plane parallel to the planes in which the plates 2 and 3 are located, however, the construction and arrangement of the parts is such that if the blade C should not be parallel but should be inclined somewhat relative to the plates when inserted therebetween, the ribs 7 and 8 will still grip and form line contact with said blade. Moreover, such line contact will be obtained regardless of how far the blade is inserted between the ribs 7 and 8. Thus a better and more efficient contact is made for the conveyance of 40 electric current.

Thus from the foregoing it will be readily apparent that I have provided a two stage contact switch wherein the pressure exerted by the side walls of the recess is relatively light while the final contact of the ribs with the blade is comparatively heavy. Similarly, when the blade is 45 50 55

withdrawn from the ribs into the cup-shaped recess the contact pressure is relieved and when the blade is withdrawn from the recess the circuit is broken.

5 While I have shown and described a switch comprising separately formed plates 2 and 3, it is apparent such plates may be integral in the form of a U or may be integral with the upright portion 6 of the terminal bar A.

10 What I claim as my invention is:

1. An electric contact anchored at one end and free at the other, said contact being provided between said ends with longitudinally spaced means for successive engagement with a cooperating contact, the means initially engageable by said cooperating contact being capable of carrying the full load until the second means is engaged and comprising substantially parallel portions formed to subject the cooperating contact to a preliminary pressure and hold the same, the means subsequently engageable by said cooperating contact comprising opposed portions disposed closer together and formed to subject said cooperating contact to a greater pressure and hold the same.

2. An electric contact anchored at one end and free at the other, said contact being provided at its free end with flaring guide means for a cooperating contact and provided between 30 said ends with longitudinally spaced means for successive engagement with such cooperating contact, the means initially engageable by said cooperating contact being adjacent the flaring guide means and comprising substantially parallel portions formed to subject the cooperating contact to a preliminary pressure and hold the same, and the means subsequently engageable by said cooperating contact being nearer to the anchored end aforesaid and comprising opposed 35 portions disposed closer together and formed to subject such cooperating contact to a greater pressure and hold the same.

3. An electric contact provided with longitudinally spaced means for successive engagement with a cooperating contact, the means initially engageable by said cooperating contact comprising

ing substantially parallel portions constructed and arranged to subject the cooperating contact to a preliminary pressure and hold the same, and the means subsequently engageable by said cooperating contact comprising opposed portions integral with the parallel portions but constructed and arranged to subject the cooperating contact to a greater pressure and hold the same.

4. An electric contact anchored at one end 10
and having flaring guide portions at its other
end, said contact being provided between said
anchored end and flaring guide portions with
longitudinally spaced means for successive en-
gagement with a cooperating contact, the means 15
initially engageable by said cooperating contact
comprising opposed portions constructed and
arranged to subject the cooperating contact to
a preliminary pressure and hold the same, and
the means subsequently engageable by the co- 20
operating contact comprising opposed portions
that are closer together than the opposed por-
tions just mentioned and are formed to subject
the cooperating contact to a greater pressure
and hold the same. 25

5. An electric contact having substantially parallel members anchored at one end and provided at the other end with flaring guide portions for a cooperating contact, said members being provided intermediate their anchored ends and flaring guide portions with longitudinally spaced means for successive engagement by such cooperating contact, the means initially engageable by said cooperating contact comprising substantially parallel portions offset inwardly relative to said members, said parallel portions being sufficiently close together to subject the cooperating contact to a preliminary pressure sufficient to hold the same, and the means subsequently engageable by said cooperating contact comprising opposed portions offset inwardly relative to the offset portions aforesaid, said opposed portions being closer together and formed to subject the cooperating contact to a greater pressure and hold the same. 45
